UNITED STATES PATENT OFFICE

JOHN HAYS HAMMOND, JR., OF GLOUCESTER, MASSACHUSETTS, AND ERNST F. W. ALEXANDERSON, OF SCHENECTADY, NEW YORK; SAID ALEXANDERSON ASSIGNOR TO GENERAL ELECTRIC COMPANY, A CORPORATION OF NEW YORK

RADIANT ENERGY GUIDING SYSTEM FOR AIRPLANES

Application filed February 15, 1928. Serial No. 254,540.

The invention relates to means for and method of guiding aerial transportation.

One object of the invention is to provide definite fields of radiant energy intensity for 5 guiding aircraft in predetermined paths.

A further object of the invention is to provide clearly defined aircraft trails without relying upon sound or light signals which may be subject to failure due to climatic 10 conditions.

A still further object of the invention is to provide electrical signaling means for defining the position of a landing field to aircraft pilots who may be above the range of 15 vision and sound from the landing field.

One feature of the invention relates to the provision of an improved radio broadcasting antenna which is adapted to propagate polarized electrical signals in a vertical 20 direction from the antenna.

A further feature of the invention relates to the provision of an electrical broadcast antenna, which is adapted to propagate electrical signals in a comparatively confined 25 direction vertically upwardly and outwardly at right angles to the length of the antenna in such manner as to produce a fan-shaped field of signal intensity extending from the antenna.

30 A still further feature relates to the provision of means for defining an aviation trail by the positioning of the plurality of antennas of a character designed to propagate vertical fan-shaped areas of signal intensity 35 whereby the edges of each fan-shaped area are adapted to lie adjacent the fan-shaped area produced by the next antenna in such manner as to provide a single continuous line of radiant energy signal intensity.

40 Another feature of the invention relates to the provision of a system of radio antennas which are designed to produce a path of signal intensity circumscribing a landing field in such manner as to advise an aircraft 45 pilot that the field lies directly below him.

Other features and objects will appear from the following description taken in connection with the accompanying drawings in which

50 Fig. 1 is a view of one preferred form of

broadcasting antenna illustrating the manner in which radio signals are broadcasted therefrom.

Fig. 2 is a view illustrating the manner in which a continuous path of signal intensity 55 is formed by a plurality of antennas as illustrated in Fig. 1;

Fig. 3 is a plan view of a system of radio signal antennas for defining landing fields and for marking paths to the said field. 60

Like reference characters denote like parts in the several figures of the drawings.

In the following description and claims, parts, characteristic features and functions will be identified by specific means for convenience of expression, but they are intended to be as generic in their application to similar parts or equivalent construction as the art will permit.

Referring to Fig. 1 of the drawings, one 70 form of radio broadcasting antenna is illustrated, which may be used in connection with this invention, as will hereinafter be described. The antenna structure comprises end poles 10 and 11 upon which are supported 75 cross arms 12 and 13, respectively. The distance between the two poles 10 and 11 is approximately twice the distance of a wavelength. The length of the cross arm is preferably one half a wavelength. Carried by 80 the ends of the cross arms 12 and 13 are a pair of supporting elements 14 and 15 to which an antenna 16 is secured. The antenna 16 is arranged, as indicated, to form a plurality of diagonals between the supporting 85 elements 14 and 15. When this antenna is operated at its natural period a field of electrical signal intensity, as illustrated by the dotted lines in Fig. 1, is produced, the character of which may best be described as 90 a fan-shaped field extending vertically at right angles to the supporting elements 14 and 15. It is desirable in this connection to use a low wave length in transmission as for instance below 10 meters whereby expansion 95 of the field in the direction of the length of the antenna will not take place. Arranged on one of the poles 11 or 12 is a box or casing 18 containing a source of oscillations such as an oscillator or chopper. Wires 19 are pro-

100

vided for impressing the oscillations on the antenna.

Referring to Fig. 2 of the drawings, for providing a continuous path of electrical signal intensity at high altitudes, a plurality of signal propagating antennas, such as the type shown in Fig. 1, are provided parallel to each other as to length and positioned with their length at right angles to the path which is desired to be formed, in the manner illustrated such that the edges of the fan-shaped field of signal intensity produced by each antenna is adjacent to the edges of the fan-shaped fields of signal intensity produced by its adjacent antennas. Thus it will be apparent that a signal path of radio signal intensity is provided. At a certain predetermined altitude the field intensity throughout the length of the path is thus equal or constant, whereas at a lower altitude, due to the shape of the radiation projected from each antenna the field intensity alternately increases and decreases as the craft moves along the course. In this way the pilot of the craft may obtain an indication of his altitude at any point on the course. It will be understood that the boxes 18 on the poles 11 are supplied with energy by a suitable cable 17 from a suitable source *a*.

In the use of such a system it is preferable to transmit simultaneously definite signals over all the antennas forming the path, such for instance as a letter of the Morse code, whereby a pilot of an aircraft traveling in or adjacent to the signal field will be guided by it through the use of the usual electrical signal receiving device and the path may be readily distinguished by the call letter or peculiar signal of the path which is being simultaneously propagated by the various antennas forming the path.

As illustrated in Fig. 3 of the drawings, a system of aviation guiding lanes and landing field indicators are provided as for instance the lanes 30, 31, 32 and 33 formed as indicated in Fig. 2 by a plurality of radio signal antennas. In such a system it is preferable that the antenna forming the guiding lane 30 transmit a signal varying from signal broadcast by the guiding lane 31 and so on for the lanes 32 and 33 of the system. Surrounding the landing field 34 is a plurality of radio antennas 35 which are adapted as set forth in connection with the Fig. 2 of the drawings to propagate vertically, a continuous path of electrical signals circumscribing the landing field. If desired a particular portion of the field may be designated by a second circumscribing signal intensity formed by an inner line of adjacent antennas 37 whereby one particular portion of the landing field may be designated to the aviator in which to land. The signals are propagated by the landing field indicating antennas 35 and 37 to be clearly characterized

from the signal propagated by the antennas forming the lane. This may be provided for by signalling the center of the landing field from the antennas 37 by the letter "A" as for instance in the Morse code. The antennas 35 may propagate the signal AA thus signifying that the pilot is entering the landing field. The lane 30 made by a combination of various letters or a letter and a number as for instance A1 indicates to the pilot that he is on lane 1 leading to air field A. Lane 31 may be designated as A2 thus signifying the pilot is approaching the landing field A on lane 2, similarly 32 and 33 may be designated in such manner as to indicate the landing field to which they lead and the path leading thereto.

In operation, the antenna 16 is energized at its natural period of wave length of less than 10 meters, whereby a field of electrical signal intensity is created extending vertically upward in fan-shaped formation at right angles to the length of the antenna structure. As a plurality of such structures are arranged adjacent to each other in such manner as to have the outer sides of the fan-shaped signal intensity areas coinciding a contiguous line of signal intensity is created forming a path at right angles to the length of the antennas involved. The signals which are adapted to be simultaneously propagated by all the antennas forming the path may be of a character as indicated which will advise an air pilot as to the path upon which he is traveling and the landing field to which it leads. A similar arrangement of antennas may be arranged to form a closed figure surrounding the landing field which antennas are adapted to simultaneously propagate a signal which will designate to the pilot that he is entering the area directly above the landing field. A second figure may be formed by another series of antennas which on entering the field the pilot will cross thus indicating to him that directly below him lies that portion of the field upon which he may land with safety.

Thus the invention provides means whereby an aviator desiring to land at a certain field may fly in the general direction of the field and by radio receiving means will be advised upon approaching one of the lanes leading to the field. The signal propagated by the antenna designating the lane or path will advise him as to the field to which it leads and the usual radio direction finder may be employed for determining which direction upon the lane he should travel to reach the field. As the lanes may be arranged in radiating formation from the field as its center it is hardly likely that the pilot will fail to cross one of the lanes when in the vicinity of the field. Thus it may be readily seen that from the information received through the radio receiving instruments and

direction finders he may follow the lane to the flying field. Upon reaching same, if climatic conditions are such that the usual visual or audible signals are not apparent he will be

5 advised upon reaching the field by the signalling systems surrounding it and will also be advised upon reaching that portion of the field upon which he may safely make a landing.

10 The invention upon which this application is based is broader than the specific embodiments shown and described for the purpose of illustrating at least some of the ways in which it may be employed. The scope of the 15 invention is therefore to be understood as not being limited by the present specific description. We intend no limitations other than those imposed by the claims.

What is claimed is:

20 1. The combination, in a system for guiding moving craft along a predetermined path, of a plurality of radiating systems arranged at intervals along said path, each of said radiating systems being adapted to project 25 a fan shaped radiation into space, said fan shaped radiation extending longitudinally of said path, the different radiating systems being spaced apart along said path to produce a substantially uniform field intensity 30 throughout the length of said path.

2. The combination, in a system for guiding aircraft, of a plurality of radiating systems arranged along a predetermined path, each of said radiating systems being adapted 35 to project a fan shaped beam into space, said fan shaped beam radiated by each of the different systems extending lengthwise of said path, said radiating systems being so spaced along said path that at a predetermined altitude said beams coincide sufficiently to produce a substantially constant intensity of radiation throughout the length of said path whereas at a lower altitude said radiation intensity along the length of said 40 path alternately increases and decreases.

3. The combination, in a system for guiding aircraft, of a plurality of radiating systems arranged along a predetermined path, each of said radiating systems being adapted 45 to project radio waves into space, the radiation pattern in a horizontal plane produced by each of said systems being relatively long and narrow and extending longitudinally of said path, said systems being spaced at intervals along said path such that the radiation patterns coincide sufficiently to produce 50 substantially constant signal intensity at a predetermined altitude.

4. The combination, in a system for guid-

ing moving craft, of a plurality of radiating systems arranged along said path each of said radiating systems being adapted to project radio waves into space along said path said radiating systems being spaced at intervals 70 along said path such that their radiation fields coincide sufficiently to produce a substantially uniform radio field intensity throughout the length of said path and a common means for controlling all of said radiation systems thereby to modulate the entire field along said path with a common signal.

5. In a system for guiding aircraft to a landing field, the combination comprising a plurality of short wave antennæ spaced along a boundary of said field, each of said antennæ being constructed and arranged to project upward from said boundary of said field a fan-shaped beam of radio waves of short wave length, and the different antennæ being so spaced and arranged relative to each other that said fan-shaped beams combine to form a continuous sheet of radio waves extending longitudinally of said boundary.

6. In a system for guiding aircraft to a landing field, the combination comprising a plurality of short wave antennæ spaced along each boundary of the landing field, each of said antennæ being constructed and arranged to project upward from the respective boundaries of said field a fan-shaped beam of radio waves, the different antennæ along each boundary being so shaped and arranged relative to each other that said beams combine to form a continuous sheet of radio waves extending longitudinally of the respective boundaries whereby the space over said landing field is enclosed by said sheets of radiation.

7. In a system for guiding aircraft to a landing field, the combination comprising a plurality of short wave antennæ spaced along a boundary of said field, said antennæ being constructed and arranged to project upward from said boundary of said field a sheet of radio waves of short wave length, said sheet extending longitudinally of said boundary, means to project upward an additional sheet of radio waves of short wave length, said sheet extending from said boundary along a predetermined course leading to said landing field and means to distinctly modulate said two sheets of radio waves.

In testimony whereof we have hereunto set 120 our hands.
